UNITED STATES PATENT OFFICE

2,377,586

BUTYROMETER

Alf Lennart Stigen, Stockholm, Sweden, assignor
to Aktiebolaget Separator, Stockholm, Sweden,
a corporation of Sweden

Application January 6, 1943, Serial No. 471,447
In Sweden January 8, 1942

2 Claims. (Cl. 73—427)

Butyrometers, used for ascertaining the fat content of, for example, milk or cream, comprise a container having a wider body portion, open at the bottom, and a narrower portion in the form of a long neck, the latter being provided with a scale on which the length of a fat column formed during the test is read off. Such butyrometers are provided with a capillary opening at the junction of the body and neck. To fill the butyrometer it is held in such position that the body is above the neck, and the sample to be tested and the reaction agent are poured into the open bottom of the butyrometer. During filling, the opening is closed by putting a finger over the open end of the neck. The liquid running down into and through the neck of course contacts with the finger, which is objectionable, because the reaction agent consists of a strong acid which is injurious to the skin. To overcome the objection, the butyrometer is sometimes placed on a stand provided with means which closes the capillary opening during filling. This expedient, however, does not establish a tight sealing; and, moreover, it has been found that there is a risk of leakage as soon as the butyrometer is removed from the stand.

According to the present invention the objections above recited are avoided by constructing the butyrometer with a wide body open at its lower end and a narrow neck open at its upper end and providing a projection on the body relatively near the neck having a through passage open to the interior of the body and constricted to form a capillary opening, in combination with a single member providing means for closing both the upper end of the neck and the outer end of the said passage while the butyrometer, in reversed position, is being filled, and a closure for closing the lower end of the body before the butyrometer is restored to upright position. Preferably, the said projection is in the form of a tube whose outer end extends in substantial parallelism with the neck, while the closing means, when the butyrometer is in reversed position while being filled, is a stand having two open-top holes having flexible walls and spaced apart a distance corresponding to the horizontal distance between the neck and tube, the holes being at relative levels corresponding to the relative levels of the upper ends of the neck and tube.

In the accompanying drawing, Fig. 1 is a longitudinal sectional view of the butyrometer in upright position and Fig. 2 is a similar view of the butyrometer, in reversed position for filling, applied to the stand for closing the neck and tube.

In the butyrometer shown in Fig. 1, the body 1, which is made of glass, is provided with a projection 2, in the form of a cylindrical tube or spout, having a capillary opening 3. The general direction of extension of the tube is parallel

with the neck 4. The wider body portion is, in the usual way, closed by a rubber stopper 5. The capillary opening 3 is closed by means of a rubber cap 6 fitted over the tube 2. The orifice of the tubular neck 4 is in similar manner closed by another rubber cap 7.

In Fig. 2 is shown a stand 11 of, for example, vulcanized rubber, on which is placed, upside down, in position for filling, a butyrometer like that shown in Fig. 1. The stand is provided with a recess 12 for the tube 2 and with a recess 13 for the neck 4. Thereby the butyrometer is held fixedly in the stand. The horizontal distances between the recesses 12 and 13 should equal the horizontal distances between the neck 4 and tube 2, and the diameter of the recesses 12 and 13 should correspond to the outer diameters of the neck 4 and tube 2, so that a tight connection is established.

What I claim and desire to protect by Letters Patent is:

1. A butyrometer comprising a relatively wide body having an open lower end and a relatively narrow neck communicating with the interior of the body and open at its upper end, a projection on the body relatively near the neck having a through passage constantly open to the interior of the body and constricted to form a capillary opening, a single member providing removable means for closing both the upper end of the neck and the outer end of the passage in the projection while the butyrometer, in reversed position, is being filled, and a closure for closing the lower end of the body before the same is restored to upright position.

2. A butyrometer comprising a relatively wide body having an open lower end and a relatively narrow neck communicating with the interior of the body and open at its upper end, a projection on the body relatively near the neck having a through passage constantly open to the interior of the body and constricted to form a capillary opening, said projection being in the form of a tube whose outer end extends in substantial parallelism with the neck, means for closing the upper end of the neck and the outer end of the passage in the projection while the butyrometer, in reversed position, is being filled, said means comprising a stand having two open-top holes whose diameters approximate respectively the diameters of said neck and tube, said holes having flexible walls and being spaced apart a distance corresponding to the horizontal distance between said neck and tube, the holes being at relative levels approximating the relative levels of the upper ends of said neck and tube, and a closure for closing the lower end of the body before the same is restored to upright position.
